UNITED STATES PATENT OFFICE

WILLIAM C. SHINN, OF CHICAGO, ILLINOIS, ASSIGNOR TO CHICAGO LOCK COMPANY,
OF CHICAGO, ILLINOIS, A CORPORATION OF ILLINOIS

DESIGN FOR A FACE PLATE FOR COIN CHUTES

Application filed March 31, 1933. Serial No. 47,655. Term of patent 7 years.

To all whom it may concern:

Be it known that I, WILLIAM C. SHINN, a citizen of the United States, residing at Chicago, in the county of Cook and State of Illinois, have invented a new, original, and ornamental Design for a Face Plate for Coin Chutes, of which the following is a specification, reference being had to the accompanying drawing forming a part thereof.

Figure 1 of the drawing is a perspective

of a face plate for a coin chute embodying the new design;

Figure 2 is a front view of the face plate; and

Figure 3 is a side view.

I claim:

The ornamental design for a face plate for a coin chute substantially as shown.

Chicago, Illinois, March 14, 1933.

WILLIAM C. SHINN.
